UNITED STATES PATENT OFFICE.

GEORGE E. ADAMS, OF NEW BRITAIN, CONNECTICUT.

DESIGN FOR A GARMENT-SUPPORTER LOOP.

SPECIFICATION forming part of Design No. 31,994, dated December 19, 1899.

Application filed November 21, 1899. Serial No. 737,816. Term of patent 7 years.

To all whom it may concern:

Be it known that I, GEORGE E. ADAMS, a citizen of the United States, residing at New Britain, in the county of Hartford and State of Connecticut, have invented and produced a new and original Design for Garment-Supporter Loops, of which the following is a specification, reference being had to the accompanying drawings, forming part thereof.

10 In the drawings, Figures 1 and 2 are obverse and reverse views of the loop embodying the present design. Fig. 3 is an end elevation of the same.

The leading or characteristic features of 15 the present design are the relatively long and narrow loop at the top, with a downwardly-tapering body portion terminating in a substantially circular apex, together with the beaded edges of the body portion and spherical projection centrally of the circular apex of the body portion on the obverse side.

The letter A indicates a long narrow loop,

a the bottom bar of the loop, having an offset portion a', and B indicates downwardly-tapering body portions extending down from 25 the offset portion a' of the loop A.

C indicates the circular apex of the body portion, and D a spherical projection arranged centrally of the said circular portion on the obverse side.

E indicates the rear or reverse side of the body portion, and F a cylindrical body extending between the obverse and reverse sides of the body portion centrally of the circular extensions.

30 G is a bead extending down each side of the body portion and circular extension.

What I claim is—

The design for a garment-supporter loop as herein shown and described.

GEORGE E. ADAMS.
